VENTILATING CABINET

Herman C. Hueglin, Chicago, Ill., assignor to
Federal Merchandise Company, Chicago, Ill.,
a corporation of Illinois

Application March 11, 1929. Serial No. 345,951

7 Claims. (Cl. 98—43)

This invention relates to ventilating cabinet, more particularly to ventilating cabinets for use in homes or small offices.

Exhaust fans have heretofore been used to improve the ventilation of certain rooms in a residence, particularly to improve the ventilation of the kitchen. These ventilators usually contain a medium size electrically driven exhaust fan travelling at a relatively low rate of speed.

10 For this purpose, several fans have been provided those fans usually being mounted within a ring shaped spider which supports the motor. To mount the fan in the kitchen it has been the custom heretofore to mount the spider of the 15 fan in a framework which is held before a window and usually near the top of it. The framework for supporting the fan frequently takes the form of a plate or board extending completely across the window frame.

20 The use of such a device has several disadvantages among which are the danger of curtains or other flexible materials being drawn into the fan and mutilated, the inconvenience of mounting and operating the fan, and the inconvenience 25 caused by the solid mounting board of the fan blocking out a considerable portion of the window thereby darkening the room.

In my present invention I have provided an 30 exhaust fan of the same general type as has been used heretofore and I have provided a mounting for the fan adapting it for insertion in the wall of the residence, so that the air in the room may be exhausted without blocking the window of the 35 room and without the accompanying dangers that are encountered when the fan is inserted in the window.

In carrying out this invention, I have provided a cabinet of suitable dimensions to be fitted in the wall of a residence, into which the cabinet 40 fits flush with both the inside and the outside surfaces of the wall. Across the inside opening of the cabinet I have provided a grating or cover to guard against the possibility of objects being drawn into the fan.

45 The fan itself is mounted on a panel which panel obstructs the outside face of the cabinet except for the area in which the blades of the fan rotate.

50 Since a ventilating cabinet of this kind is installed as a part of the wall of the residence it is necessary to provide a cover or door which will effectively block the fan opening during inclement weather and during periods when it is 55 not desired to use the fan. To accomplish this

purpose I have provided a door hinged to the mounting panel, which door swings outward from the panel. Since the door is hinged at the upper end of the panel when it is in its outward position it serves as an awning projecting outward 60 to guard the fan opening against the entrance of rain or snow. The awning also shields the opening against sunlight without obstructing the flow of air through the ventilator.

In the usual installations of this kind the fan 65 is placed relatively high in the room, that is near the ceiling, to exhaust the warm air and steam of cooking from the room. The fan so located is in a more or less out of the way place and to facilitate operating the same I have provided a 70 relatively long lever arrangement which extends down within easy reach.

By pushing up on this lever the door covering the fan opening is opened and by the operation of the door, a switch is closed to start the fan in 75 motion. When it is desired to stop the fan, the lever is pulled down and the door closed. The closing of the door reoperates the electric switch to turn off the fan. By this arrangement it is impossible to run the fan unless the door is open, 80 a very desirable feature since when the fan is running an outlet must be provided for the air moved by it if it is to be of any service in ventilating the room. The necessity of closing the door to stop the fan guards against damage to the 85 home due to rain being driven into the fan opening when the fan is not running, as would be likely to happen if it were possible to stop the fan without closing the door.

Two embodiments of the invention are shown 90 in the accompanying drawings, the one being the preferred form of cabinet used in case the wall in which the cabinet is already built and not provided with an opening suitable for the cabinet. The other embodiment is preferred for new installations wherein a suitable wooden frame has been incorporated in the wall to receive the ventilating cabinet. The former embodiment includes a flanged collar which is adjustably fastened to the cabinet to permit fitting the cabinet 95 in walls of varying thickness. In the latter embodiment the collar is omitted since the wooden frame can be varied to compensate for different wall thicknesses.

100 Figure 1 shows an elevation view of the cabinet as it would appear from the inside of a room.

105 Figure 2 is a cross-sectional view of Figure 1 taken along the line 2—2 looking in the direction of the arrows,

Figure 3 is a cross-sectional view of a portion of the cabinet frame taken along the line 3—3 of Figure 1.

Figure 4 is another sectional view of the cabinet frame taken along the line 4—4 of Figure 3.

Figure 5 is a detailed section of the operating lever taken along the line 5—5 of Figure 2.

Figure 6 is a detailed section of the hinge for attaching the operating lever to the door of the cabinet taken along the line 6—6 of Figure 2, and

Figure 7 is an enlarged view of the operating lever showing the latching devices.

Figure 8 is a cross-sectional view showing the cabinet installed in a wooden frame work provided for it in the wall of a building.

The cabinet is constructed of sheet metal member 1 which has the flange 1' bent in one of its edges. Four of these members 1 form the four sides of the rectangular cabinet, the sides being welded or riveted together at the corners. Mounting brackets 6 are attached to the side members 1 inside the flange 1', the brackets being placed at the corners of the cabinet. The grating 2 is set over the flange 1' to close the one face of the cabinet, being held on the flanges by the screws 6' extending through it and the mounting brackets 6. The edges of the grating overhang the cabinet at 3 to form a flange which will fit snugly up against the wall in which the cabinet is mounted.

The opposite face of the cabinet is closed by the plate 7 the edges of which are bent to fit over the ends of the side walls 1 with the flange 7' of the plate disposed on the outside of the walls. Plate 7 is held on the cabinet by welding or riveting the flanges to the side walls.

Disposed in the center of the plate 7 is a large circular opening into which the mounting ring 48 of the fan is fitted and held by the screws 9. In the preferred embodiment of my invention I use an exhaust fan of the type shown in my copending application Serial Number 289,573, filed June 30, 1928, although any exhaust fan of suitable size may be substituted therefor.

Attached to the outward face of the mounting plate 7 is the door 8 which is hinged at 8' to the upper edge of the mounting plate. This door 8 comprises a sheet metal door the edges of which are reinforced by a strip of sheet metal 12 welded to the door. The hinges 8' may be simple strap hinges or if desired a single piano hinge extending completely across the top of door may be used. The door is provided with hinge bracket 13 which extends through a slot in the plate 8, and which has a foot 13' bent over flush with the outer face of the plate 8 and spot welded thereto.

An electric switch 10, is attached to the mounting plate 7 by means of screws, in such a position that the operating lever 11 of the switch 10 is pushed into the switch by the door 8 when the latter is in its closed position. When the door is opened, the lever 11 is pushed out by a spring within the switch to operate the switch and close an electrical circuit through it. Commercial switches of this type which are in common use as door switches in closets, telephone booths and the like, are particularly well adapted for use as a door switch in the instant application, and are of sufficient capacity to carry the current required by the preferred fan motor.

The door 8 is operated by a system of levers comprising the straight bar lever 15 which is pivotally riveted at 14 to the hinge bracket 13 on the door, and the L-shape operating lever 17 which is pivotally hinged at 27 to the mounting bracket 28 which is attached to the frame mem-

ber 1 of the cabinet by screws or rivets. The free end of the lever 15 is pivotally connected at 16 to the operating lever 17, and the other end of the lever 17 is provided with the pivot bearing 18.

The levers 15 and 17 project through a rectangular slot 15' in the mounting plate 7 near the end of the cabinet on which the bracket 28 is mounted. As can be best seen in Figures 5 and 7, the pivot bearing 18 loosely fits in the slot 19 in the operating lever 21. The coil spring 20 has one end wrapped around the pivot 18, and the other end attached to the rod 21 by the screw 22. This spring is tensioned so that the pivot 18 is normally maintained in the lowermost position of the slot 19 for a purpose which will be apparent hereinafter.

The operating lever 21 is provided with the lip 23 projecting from its side at a point adjacent to the lower part of the cabinet. A latch bracket 24 is fastened on to the front plate 2 of the cabinet by the screw 26 extending through the latch 24, the plate 2 and the mounting bracket 6. The latch 24 is provided with the slot 25 through which the lever 21 projects. When the door is closed, as shown by the solid lines in Figure 2, the operating lever 21 is in its lowermost position with the lip 23 below the latch 24. The spring 20 is tensioned and the pivot 18 is moved to the upper end of the slot 19. By pressing the lever 21 towards the cabinet 1, the lip 23 can be made to engage the under edge of the bracket 24 back of the slot 25 to enable the lip 23 to latch the door in its closed position. The lip 23 is held securely against the bracket by the tension of spring 20.

Inasmuch as the cabinet will most likely be placed in a high and rather inaccessible place the rod 21 is extended by the handle 29 which is attached to it by screws or rivets. Handle 29 may be of any length suitable to bring it in easy reaching distance from the floor. When it is desired to open the latched door, the rod 21 is pulled outward from the cabinet to unlatch the lip 23 from the latch 24 and to permit the lip to pass through the slot 25 in the latch. A slight upward pressure on the rod 21 moves the L-shape lever 17 about its pivot 27, causing the pivot 16 to move in a counter-clockwise direction and push the lever 15 acting outward. Lever 15 through pivot 14, pushes the door 8 on its hinge 8', the final position assumed by the door and levers being shown by dotted lines in Figure 2.

In passing from one extreme position to the other as the door is opened, the levers 15 and 17 pass through the point in which they are aligned with each other and come to rest after they have been moved a few more degrees. That is their bottom edges are moved through a straight angle into an obtuse angle. With the levers so positioned the bottom edge of lever 17 rests against the bottom edge of the slot 15'.

The weight of the door 8 bears on lever 17 through lever 15 to hold 17 against the edge of the slot thereby locking the door in its open position. As previously pointed out, an operation of the door 8 from its closed to its open position operates the switch 10 to close the electric circuit to the motor to thereby start it.

In instances where the ventilator is installed in a new building, it is preferable to provide a wooden frame 40 in the wall 42, as shown in Figure 8. This frame can be incorporated in the wall 42 when the latter is built, to afford a firm support for the ventilating cabinet. Preferably

in an installation of this kind the cabinet 1 will be placed in the frame before the plaster is put on so that the plaster will seal the space intervening between the cabinet and frame, thereby 5 making a tight fitting installation. The fan, switch, cabinet door, levers, and grating are to be installed after the building is completed.

If the wall is thicker than the cabinet 1, the frame 40 projects outward beyond the door 8 10 on the top and sides of the cabinet, and the sloping sill 41 is provided at the bottom of the cabinet. Such an installation protects the cabinet against the entrance of rain and snow, as will be apparent.

15 When it is desired to mount the cabinet in an existing wall, as for instance adding the ventilator to a house that is already built, the use of a wooden frame such as 40 may prove to be undesirable because of the difficulty in securing 20 the frame in the wall. For installations of this kind, I have provided the flange collar 4 which fits around the cabinet 1 and is provided with the outwardly projecting flange 5. As will be best seen in Figs. 3 and 4, the collar 4 is provided with a slot 30' through which the machine bolt 30 projects. The machine bolt also projects through a hole in the cabinet 1, and a nut is threaded on it within the cabinet. The collar is thereby made adjustable with respect to the 25 cabinet 1, so that the distance between the flange 5 of the collar and the overhang 3 of the grating may be varied to bring the flange and the overhang flush with opposite sides of the wall in which it is desired to mount the cabinet. With 30 this adjustment made tightening the screws 30 or the nuts on the screws locks the collar with respect to the cabinet to thereby lock the cabinet in the wall. By suitable design of slot 30' the collar may be adjusted with respect to the cabinet 40 through a sufficient range to permit mounting the cabinet in walls varying in thickness from six to twelve inches, which variation is within the range of variations encountered in residences and the like. Preferably the flange 5 which fits 45 on the outer face of the wall, is covered by a moulding or similar framework to protect against the entrance of rain or snow between the flange and the wall. The use of the collar 4 instead of the wooden frame work 40, makes the installation 50 of the cabinet in an existing wall much simpler and therefore cheaper.

With the constructions shown and described a ventilating cabinet can be cheaply made and easily installed in a home. I prefer to construct 55 the cabinet of sheet iron, and to protect the iron by painting, the paint to match the color of a room in which the cabinet is to be used. While I have chosen to show a preferred embodiment of my invention, I have done so by way of example 60 only as there are many modifications and adaptations which can be made by one skilled in the art without departing from the teachings of the invention.

Having thus complied with the statutes and 65 shown and described a preferred embodiment of my invention, what I consider new and desire to have protected by Letters Patent as pointed out in the appended claims.

What is claimed is:—

70 1. In a ventilating cabinet, a door hinged to one side of the cabinet, a lever pivoted to said door, an L-shape lever pivoted to the cabinet and having one of its ends pivoted to the free end of said door lever, a rod having a slot near one 75 of its ends, a pivot attached to the free end of

said L-shape lever and disposed in said slot to slidably connect the lever to the rod, a coil spring attached to said rod and latter pivot to keep the pivot at one end of the slot, a lip projecting from said rod, a bracket attached to said cabinet having a slot through which said rod slides to operate said levers to close said door, said lip passing through said slot and engaging on the under side of said bracket under the tension of said spring to hold the door closed. 80

2. In a ventilating cabinet, a panel having an opening therein, a fan having a mounting rim fitted into said opening, a motor for said fan, a door hinged to said panel, levers extending through said cabinet and attached to said door, a switch mounted on said panel and having an operating rod engaged by the door in its closed position to open the switch and disengaged by the door in its open position to close the switch, and a circuit for said motor controlled by said switch. 85

3. In a ventilating cabinet, a door hinged to the cabinet, a straight lever pivoted to the door, an L-shaped lever pivoted to the cabinet, a pivoted connection between said levers, means for 100 rotating said L-shaped lever about its pivot to open said door and to align the door lever with one arm of the L-shaped lever to lock the door in its open position, an operating lever connected to the other arm of said L-shaped lever, guide means 105 for said operating lever, and means on said lever adapted to cooperate with the guide means for locking the door in its closed position.

4. A ventilating cabinet comprising a rectangular frame, a collar adjustably fitted over said frame and having a flange projecting outwardly from one of its edges, a panel fitted over one face of said frame, a switch, a door and an electric fan mounted on said panel, a grating fitted over the opposite face of said frame, said grating having edges overhanging said frame which cooperate with said flange to hold the cabinet in a wall, a lever projecting through said grating, and means controlled by said lever for controlling said door, switch and fan. 110

5. The combination of a ventilating cabinet, a fan mounted therein, a door hinged to one side of said cabinet, a door switch opened by the door in its closed position for controlling the fan, lever means connected to said door and projecting 115 through the opposite side of the cabinet to the outer side thereof, a guide bracket on said cabinet, a slotted operating lever extending through the guide bracket and associated with the lever means for imparting opening and closing movements to said door through said lever means, means on said operating lever adapted to cooperate with said bracket to restrain movement of the operating lever for opening movement of the door, and a lost motion connection between said 120 lever means and said operating lever including a pin on said lever means fitted in the slot in said operating lever whereby said operating lever may be selectively positioned to either freely retain the door in closed position or to lock the door in 125 closed position. 130

6. The combination of a ventilating cabinet, a fan mounted therein, a door hinged to one side of said cabinet, lever means connected to said door for opening and closing the same and having an operating portion extending from said cabinet, a guide secured to said cabinet and having a slot receiving the operating portion of said lever means, a toggle joint included in said lever means and operative when said door is raised to full 140 145 150

open position to hold said door against said closing, and a detent on the operating portion of said lever means engaging said guide to lock said door in closed position.

5 7. In a ventilating cabinet having a fan mounted therein and a door hinged to one side of said cabinet, the combination of a plurality of levers for opening and closing said door including a

toggle connection for holding said door in full open position, a lost motion connection between two of said levers for releasing said door from full open position upon operation of said levers, lock means for holding said door in closed position, and resilient means for holding said lock means under tension when said door is closed.
